TYPEWRITER ATTACHMENT

Louis Jensen, Chicago, Ill., assignor to United Autographic Register Co., a corporation of Illinois

Application January 13, 1933, Serial No. 651,592

9 Claims. (Cl. 197—126)

This invention relates particularly to typewriters adapted to the purpose of filling in forms on continuous-form stationary, and more particularly to an attachment for facilitating the shifting of a carbon pack from a filled set of forms to a succeeding set of forms.

The present invention is an improvement on the device shown in my co-pending application, Serial No. 571,747, filed October 29, 1931.

10 The primary object is to provide improved means for holding the continuous-form stationary so that it will not be necessary for the operator to reach very high above the machine to retract interleaved transfer sheets from an advanced to succeeding set of forms. In the present invention the stationery holding means is in the form of a telescopic standard which need only be extended during the transfer sheet retraction operation.

20 In accordance with the present invention, after a set of forms has been filled in, the end of the strips advance into engagement with a paper clip, and upon release of the platen presser-means, the operator may grasp a handle extending downwardly from the paper clip and advance the forms into a position where the carbon sheets may be retracted from the advance set of forms into interleaved relation with the next set of forms. The freshly loaded set of forms may 30 then be retracted to writing position by means of the platen roll and associated presser-means, the paper clip being drawn downwardly to the end of its travel and allowing the stationery to slip from its grasp. The completed set of forms 35 may then be detached.

The invention is illustrated in a preferred embodiment in the accompanying drawings, in which—

Fig. 1 is a front elevational view of a machine 40 embodying the invention; Fig. 2, a side elevational view of the same; Fig. 3, a broken sectional view taken as indicated at line 3 of Fig. 1; Fig. 4, a fragmentary sectional view showing the standard supporting means, taken as indicated at line 4 of Fig. 3; Fig. 5, perspective view of the improved device; Fig. 6, an enlarged vertical sectional view of the paper clip taken as indicated at line 6 of Fig. 7; Fig. 7, a sectional view taken as indicated at line 7 of Fig. 6; Fig. 50 8, a sectional view taken as indicated at line 8—8 of Fig. 6; Fig. 9, a broken longitudinal sectional view of the telescopic standard; Fig. 10, a fragmentary elevational view of the spring catch which holds the extensible portion of the 55 standard; and Fig. 11, a modified form of the

adapter-bracket which enables the device to be attached to various standard makes of typewriters.

In the embodiment illustrated, A designates a main frame of a typewriting machine; B, a shiftable platen carriage having a platen B', and a tabulating rock-bar B² upon which the attachment is mounted; C, a stationery supporting device having rearwardly extending guide frame C', and adapter-brackets C²; and D, a telescopic standard equipped with an extensible member D' having at its upper end a downwardly projecting handle D² and a paper clip D³.

The typewriter A and shiftable carriage B may be of the conventional type provided with a platen roll B' and a tabulating rack-bar which is usually equipped with adjustable stops for use in connection with tabulating operations on the typewriter.

The attachment C may be in the form of a 75 loop, preferably made of a flat bar whose end portions 12 are turned upwardly and may be clamped together by means of a screw 13 equipped with a finger nut 13^a. The guide frame C' may have a central standard 14 spot welded, or otherwise rigidly mounted on the loop C, and supports a U-form guide 15 at its rear portion by means of a clamp 14^a and bolt 16. The lower portion of the loop C is equipped with a series of tapped holes 17 which enable various forms of adapter 80 brackets C² to be attached thereon. Preferably, the adapters are fastened to the frame C by means of thumb screws 18 and sliding keepers 19. The lower end of the adapters are of U-form, so as to slip over the tabulating bar D² and are 85 equipped with set screws 20 so that they may be rigidly mounted thereon.

It will be understood that the standard form of device may be mounted on practically any of the various makes of typewriters by merely employing the proper adapter brackets C². In Fig. 11, a modified form of bracket C³ is shown which permits the device to be mounted on a machine whose tabulator bar is in a higher position than that shown on the typewriter illustrated in Figs. 100 1—3.

The telescopic standard D is equipped with a rigidly connected supporting bracket 21 having reinforcing ribs 21^a and a slot in its end portion 21^b adapted to slip over the screw 13 so 105 that the standard may be readily removed by loosening the finger nut 13^a. The rear end of the bracket is flared outwardly at 21^c, as indicated in Fig. 4, so that the standard will always 110 assume the same angle with respect to the frame 110

C. The standard D is of U-form except at its upper end portion where the marginal portions 22 are turned inwardly to form a guide for the inverted U-form extensible member D'. The 5 lower portion of the channel D' is provided with a stop 23 which engages the lower end of the marginal portions 22 of the standard D. A leaf spring 25 is fastened to the inside of the channel D by means of rivets 25^a, and the lower end portion 10 of the spring is provided with a projection 25^b which is adapted to snap under the stop 23 and yieldingly hold the member D' in its uppermost position. The upper end of the spring 25^c is adapted to bear against the inner side of the 15 channel D' and apply friction thereto.

The handle-member D² may be formed of heavy wire, if desired, and the lower end 26 may be in the form of an outwardly extending loop which is adapted to serve as a guide and hold 20 the paper along the standard D. The upper portion 27 may be in the form of a yoke having its end portions 27^a bent rearwardly and inwardly to form a pivotal connection with the member D'. If, for any reason the handle D² is not desired, it may be swung over the top of the standard D or may be removed by simply spreading the yoke 27.

A sleeve 30 is crimped around the upper end portion of the member D' and forms a stop 30 which abuts against the upper end portion of the standard D. The upper rear portion of the sleeve 30 may be cut away at 30^a to permit the paper clip D³ to engage the member D'.

The paper clip D³ has its base portion 31 looped 35 around the member D' and extends outwardly and downwardly to provide a journal 31^a and stops 31^b. The cap screw 32 extends through a tapped hole in the base 31 and screws against the member D'. A hollow guide member 33 is provided with trunnions 33^a which extend through 40 the journals 31^a. A plunger 34 is provided with a shank 34^a which extends through the guide 33 and is threaded at its outer end and engaged by thumb screw 35. A spring 36 is interposed 45 between a shoulder of the plunger and the guide 33 so as to urge the plunger downwardly towards the sleeve 30. Preferably, the plunger 32 is of square cross section so as not to turn with relation to the guide 33. The plunger is further provided with a boss 34^b which is engaged by a compression spring 37 and urges the plunger against 50 the stop 31^b. The upper end of the spring 37 is engaged by a pair of fingers 31^c which are struck inwardly from the member D³.

55. It will be understood that when paper strips 40 are projected upwardly into the jaws of the paper clip, the plunger 34 will be swung upwardly against the slight compression of the spring 37. However, when the strips are withdrawn the plunger is urged downwardly therewith and exerts a snubbing action which requires considerable force to overcome. This toggle-like movement compresses the spring 36, but if sufficient tension is exerted on the strips, they may be slipped out of the grasp of the device. The device may be adjusted to accommodate various thicknesses 60 of paper by movement of the nut 35 which may be held in a desired position by lock washer 35^a.

Operation

70 Preferably, the extensible member D' is retracted while a set of forms are being filled in so that it will not be swinging in the air due to the abrupt movements of the typewriter carriage.

75 As the sets of forms 40, loaded with transfer

sheets 41 are fed upwardly beyond the platen, they will be advanced into the jaws of the device D³ and automatically engaged by the plunger 34. The operator may then release the presser means, grasp the handle 26 and draw a fresh set of forms upwardly beyond the platen. The transfer sheets may be grasped at their marginal portions and retracted into the next set of forms. The projection 25^b of the spring 25 will exert sufficient pressure on the member D' to prevent its being retracted during this operation. The operator then engages the platen presser-means and backs the loaded set of forms into writing position. This force will be sufficient to retract the extension D' until the sleeve 30 engages the end of the standard D. Continued rearward movement of the platen will be sufficient to withdraw the ends of the strips from engagement with the member D³.

90 One of the principal advantages of the present construction is in that the operator does not have to reach two forms lengths above the platen in using the device, as was the case when the earlier forms of device were employed. In case it is desired to place a cover over the typewriter 100 or move the machine into a typewriter desk, the standard D may be removed by simply loosening the thumb screw 13^a.

95 The foregoing detailed description is given for clearness of understanding only, and no unnecessary limitations should be understood therefrom, but the appended claims should be construed as broadly as permissible, in view of the prior art.

What I regard as new and desire to secure by Letters Patent is:

1. In combination with a typewriting machine provided with a shiftable carriage having a platen roll mounted therein; means for facilitating shifting of transfer sheets comprising a standard mounted on said carriage having a fixed section 115 and an extensible section, said extensible section being provided with a downwardly extending arm adapted to serve as a guide for the stationery and as an actuating handle; and gripper means on the end portion of said extensible section for releasably engaging the advance end of 120 stationery advanced beyond said platen.

2. In combination with a typewriting machine provided with a shiftable carriage having a platen roll and a transversely disposed tabulating rack-bar mounted therein: a standard mounted on said rack-bar comprising a fixed section and an extensible section slidably mounted on the fixed section; a paper clip on the upper portion of said extensible section for gripping stationery advanced beyond said platen; and a downwardly extending guide-arm, mounted on said extensible section near said clip, and adapted to serve as an actuating handle for said extensible section.

3. In combination with a typewriting machine having a shiftable carriage provided with a platen roll and tabulating rack-bar, a stationery supporting device comprising: a loop-shaped base member provided with a rearwardly extending stationery guide frame and a pair of adapter-brackets for engaging said tabulating rack-bar; and a centrally disposed telescopic standard mounted on the base-member, said standard having a sliding extensible member provided at its upper end with a paper-clip and said standard having a pivotally mounted guide-arm adapted to serve as a handle for moving said extensible member.

4. Mechanism as specified in claim 3, in which

the adapter-brackets are each attached to the base-member by means of a thumb screw and a slidably mounted keeper.

5. A strip-gripping device comprising: a C-frame; and a snubbing arm comprising a guide-member pivotally mounted in the end portion of one of the jaws of said frame, a slide-member carried by said guide-member, a spring urging said slide-member downwardly, and an adjusting screw for limiting the downward travel of said slide-member.

6. A sheet-gripping device comprising: a base-member having an overhanging arm; a guide-member having trunnions journaled in said arm; 15 a plunger slidably mounted in said guide, said plunger being provided with an adjusting-nut to limit its travel towards the base-member; a spring urging said plunger towards said base-member; and another spring tending to swing 20 said plunger about said trunnions.

7. In combination with a typewriting machine equipped with a shiftable carriage having a platen roll and associated presser-means mounted therein; a telescopic standard mounted on said carriage having a fixed section and an extensible section mounted thereon; spring means adapted to hold yieldingly said extensible member in extended position; a stop for limiting the downward travel of the extensible member; and paper-gripping means adapted to engage the advance 30 end of stationery advanced beyond said platen,

said paper-gripping means being adapted to grip the stationery sufficiently to cause the extensible member to be retracted against said stop when the paper is retracted around said platen and upon further retraction of the stationery to permit 80 said stationery to slip from its grasp.

8. In combination with a typewriting machine provided with a shiftable carriage having a platen roll mounted therein; means for facilitating the shifting of transfer sheets comprising a standard 85 mounted on said carriage having a fixed section and an extensible section, gripper-means on the end portion of said extensible section for releasably engaging the advance end of stationery advanced beyond said platen, and an automatically releasable spring catch for holding the extensible section in extended position, said catch providing less resistance to retraction of the extensible section than the gripper-means exerts 90 on the stationery so that the extensible section 95 may be retracted by said stationery.

9. A strip-gripping device comprising: a C-frame; a snubbing arm oscillatably mounted in one of the jaws of said frame, a spring urging extension of the snubbing arm against the opposite 100 jaw of the frame, and a second spring urging oscillation of said arm into contact with said opposite jaw.
